UNITED STATES PATENT OFFICE

JOHAN ANSHELM GRANSTEDT, OF SJALEVAD, SWEDEN, ASSIGNOR TO GUNNAR PER OLOF FOGELQVIST, OF SUNDSVALL, SWEDEN

MOTOR VEHICLE

Application filed March 29, 1929, Serial No. 351,096, and in Sweden November 12, 1927.

This invention relates to motor vehicles for high speed, particularly flying machines.

The object of the invention is to reduce the formation of vacuum behind the vehicle body 5 the said vacuum originating an increased air resistance and a formation of eddies causing waste of energy.

It has already been proposed to reduce said inconveniences by giving the body of the vehicle a "stream-line" shape having the stern tapered backwards, but the formation of vacuum and the air resistance caused thereby have yet been very great, particularly at high speeds.

15 According to the invention the said inconvenience is reduced to a minimum by providing two propellers at the rear end of the vehicle body having their shafts directed obliquely in relation to the longitudinal direction 20 of the vehicle, and a guide blade apparatus behind each propeller said guide blade apparatus having all of the outer edges of its guide blades outside the vertical sides of the vehicle body.

25 The air currents originated by said two propellers are blown into said guide blade apparatus and turned rearwards therein thus forming a backward directed air current to fill the vacuum behind the vehicle body and 30 generating a force which propels the vehicle.

In the annexed drawings one embodiment 35 of the invention is shown as applied to a flying machine. Fig. 1 shows a side elevation of a flying machine having a propeller device according to the invention. Fig. 2 is plan of Fig. 1, partly in section.

The body 1 of the flying machine has parallel vertical sides in contrast to the usual "stream-line" designs and is provided with 40 a main propeller 2 in its tapering fore end in well-known manner. The upper and lower sides of the body 1 are extended rearwards to horizontal planes 3, which widen rearwards and project behind and outside the remaining parts of the body. Outside said planes 3 two additional propellers 4 are provided having their shafts directed obliquely forwards in relation to the longitudinal direction 45 of the flying machine and journalled in vertical supports or posts 5 between the

planes 3 and in bearings 6 in the body. The propellers 4 are driven from the motor shaft 8 of the flying machine by means of suitable transmissions, for instance bevel gearings 7. The planes 3 are joined by vertical studs or posts 9 which are as well as the propeller supports 5 formed as guide blades for the air currents. The vertical sides of the body are between the planes 3 formed as curved walls 10 of such shape that the air currents are turned backwards while forming a minimum of eddies. The rudder 11 of the flying machine is hinged to the rear end of the body. 55

The device described functions as follows: During the flight air currents of high speed 60 are driven by the propellers 4 laterally into the air guide apparatus 3, 5, 9, 10 said currents leaving the flying machine substantially in rearward direction. Thus, the formation of vacuum behind the flying machine and the origination of eddies are reduced as much 65 as possible. The air currents, when turned backwards between the guide blades and along the surfaces 10, originate a component 70 of force which is directed forwards and, thus, aid in propelling the flying machine. The usual propeller 2 can, therefore, be less than that of normal flying machines of the same size. 75

Instead of the usual formation of vacuum 80 behind the flying machine decreasing the speed thereof a propelling force is attained when a device according to the invention is used. Simultaneously the advantage is obtained that a higher steering effect than that 85 of ordinary flying machines is attained because strong air currents sweep along the sides of the rudder, which in contrast therewith in ordinary flying machines is placed in the vacuum behind the flying machine. Moreover, the space in the body of the flying machine is more spacious and easier to utilize 90 effectively because the vertical sides of the body are parallel and do not converge backwards. 95

The invention is not limited to the embodiment shown and described but can be modified in various manners within the scope of 100 the invention. The invention is, of course,

also applicable to other motor vehicles of high speed than flying machines.

What I claim is:—

1. In a motor vehicle for high speed, a body, two propellers at the rear portion of said body having their shafts directed obliquely forwards in relation to the longitudinal direction of the vehicle, and a guide blade apparatus behind each of said propellers, said guide blade apparatus having all of the outer edges of its guide blades outside the vertical sides of the vehicle body.
2. In a motor vehicle for high speed, a body, two propellers at the rear portion of said body having their shafts in the same horizontal level and directed obliquely forwards in relation to the longitudinal direction of the vehicle, two horizontal planes widened rearwards on level with the upper and lower sides of said body respectively, vertical posts forming guide blades between the outer edges of said planes, and curved rear walls of said body, all of said posts having their outer edges outside the vertical sides of said body and behind said propellers.
3. In a motor vehicle for high speed, a body, two propellers at the rear portion of said body having their shafts in the same horizontal level and directed obliquely forwards in relation to the longitudinal direction of the vehicle, two horizontal planes widened rearwards on level with the upper and lower sides of said vehicle body respectively, vertical posts forming guide blades between the outer edges of said planes, bearings for said propeller shafts in two of said posts, and curved rear walls of the vehicle body, all of said posts having their outer edges outside the vertical sides of said body and behind said propellers.
4. In a motor vehicle for high speed, a body, a main propeller at the fore end of said body, a motor for said main propeller, two propellers at the rear portion of said body having their shafts in the same horizontal level and directed obliquely forwards in relation to the longitudinal direction of the vehicle, transmissions between said propeller shafts and the motor of the vehicle, two horizontal planes widened rearwards on level with the upper and lower sides of said vehicle body respectively, vertical posts forming guide blades between the outer edges of said planes, bearings for said propeller shafts in two of said posts, and curved rear walls of the vehicle body, all of said posts having their outer edges outside the vertical sides of said body and behind said propellers.

In testimony whereof I have signed my name.

JOHAN ANSHELM GRANSTEDT.
